UNITED STATES PATENT OFFICE.

GEORGE A. ENSIGN, OF DEFIANCE, OHIO, ASSIGNOR TO DEFIANCE MACHINE WORKS,
OF DEFIANCE, OHIO.

WHEEL-RIM-JOINTING MACHINE.

1,037,748.

Specification of Letters Patent.

Patented Sept. 3, 1912.

Application filed April 6, 1912. Serial No. 688,881.

To all whom it may concern:

Be it known that I, GEORGE A. ENSIGN, a citizen of the United States, and a resident of Defiance, in the county of Defiance and State of Ohio, have invented a new and Improved Wheel-Rim-Jointing Machine, of which the following is a full, clear, and exact description.

The invention relates to woodworking machines, and its object is to provide a new and improved wheel rim jointing or truing machine more especially designed for jointing or truing one side of the wheel rim stock to render the said side true with the inner surface of the stock so that any inequalities due to bending or shrinkage are compensated for and the stock is provided with a true working surface to permit of subsequently feeding the stock correctly through a planer to insure the perfect formation of perfect wheel rims.

For the purpose mentioned use is made of a revoluble cutter head having cutting edges extending in the same plane, a rim stock support having movement toward and from the said cutter head and provided with spaced supporting means arranged at a right angle to the face of the cutter head and adapted to support the rim stock at the inner surface and at opposite sides thereof, and a presser device adapted to engage the rim stock exteriorly at the middle thereof, that is, approximately at a point midway between the supported points so that the rim stock is equalized and one side thereof is presented to the cutters of the cutter head to reduce the said side perfectly true relatively to the inner face of the rim stock.

A practical embodiment of the invention is represented in the accompanying drawings forming a part of this specification, in which similar characters of reference indicate corresponding parts in all the views.

Figure 1 is a perspective view of the wheel rim jointing or truing machine; Fig. 2 is a cross section of the same; Fig. 3 is a sectional front elevation of the same on the line 3—3 of Fig. 2; Fig. 4 is a sectional plan view of the same on the line 4—4 of Fig. 3; Fig. 5 is a sectional front elevation of the same on the line 5—5 of Fig. 2; Fig. 6 is a front elevation of the saddle and the supporting plates arranged for truing short stock on both sides to reduce the stock to a predetermined width; Fig. 7 is a plan view

of the same; and Fig. 8 is an enlarged sectional elevation of the same on the line 8—8 of Fig. 7.

Wheel rim stock after being bent into approximately semicircular shape by a suitable bending machine is liable to become twisted or otherwise distorted owing to the tendency of the stock to straighten out or to shrink or to do both. The truing or jointing machine presently to be described in detail is used for equalizing the distorted rim stock and to provide the same with a working side which has been reduced so as to be true to the inner surface of the stock so that the rim stock can subsequently be fed along the said working side through a rim planer and through other machines to ultimately insure the production of accurate wheel rims.

The improved wheel rim jointing or truing machine is mounted on a suitably constructed frame A in which is journaled a cutter head spindle B carrying a cutter head C provided at its face with radially-disposed cutters C', the cutting edges of which extend approximately in the same vertical plane. The cutter head spindle B is provided with fast and loose pulleys D connected by a belt with other machinery for imparting a rotary motion to the spindle B and the cutter head C, the belt being adapted to be shifted from the fast to the loose pulley and vice versa by a suitable belt shifter E under the control of the operator and mounted to swing on the frame A.

The rim stock F bent into approximately semicircular shape and of a width for producing a number of wheel rim sections is placed with its inner surface on spaced supporting plates G and G' arranged parallel to each other and standing at a right angle to the face of the cutter head C, and the top of the rim stock F is engaged by a presser device, preferably in the form of an arm H, bearing down on the top of the rim stock F at a point approximately intermediate the supported points of the inner face of the rim stock F so that the rim stock F is practically equalized on the supporting plates G and G' and consequently the inner surface of the rim stock is in a true position relative to the face of the cutter head C so that when the rim stock F is fed against the knives C', the latter trim the corresponding side of the rim stock directly through to the inner surface thereof thus providing a true work-

100

105

110

ing surface to permit of subsequently feeding the stock correctly through a planer to insure the formation of accurate wheel rim sections.

- 5 The supporting plates G and G' are preferably provided with roughened faces and are held in grooves formed in blocks I and I' secured by bolts I² to the top of a slide J provided at the under side with bearings J' mounted to slide on guideways K' on top of a saddle K provided at its rear with a bearing K² (see Figs. 2 and 4) engaging a guideway A', formed on the main frame A. The blocks I and I' are adjustable 15 toward or from each other on the top of the slide J and the blocks are for this purpose provided at their under sides with tongues I³ engaging a corresponding groove J² on the top of the slide J (see Fig. 2), and 20 the bolts I² extend through elongated slots I⁴ in the said blocks (see Figs. 1 and 7). By the arrangement described the supporting plates G and G' can be adjusted to accurate position on opposite sides of the longitudinal center of the machine.

In order to feed the rim stock F in engagement with the cutting edges of the cutters C' the following arrangement is made: On the under side of the slide J is secured 30 a rack J³ in mesh near its outer end with a pinion J⁴ secured on a shaft J⁵ journaled in suitable bearings arranged on a bracket K³ bolted or otherwise fastened to one side of the saddle K. A handle J⁶ is attached to 35 the outer end of the shaft J⁵ to permit the operator to impart a turning motion to the shaft J⁵ and thus cause the pinion J⁴ to impart a traveling motion to the rack J³ and consequently to the slide J to feed the stock 40 F toward the face of the cutter head C or away from the same after the inner side of the stock F is reduced by the action of the cutter C'.

The saddle K is adapted to be raised or 45 lowered according to the diameter of the rim stock to be trued. For the purpose mentioned the under side of the saddle K is provided with a bearing K³ (see Figs. 2 and 3) in which is mounted to turn the 50 head L' of a vertical screw rod L screwing in a nut L² mounted to turn in a bearing A² bolted or otherwise secured to the main frame A, and on the said nut L² is secured a gear wheel L³ in mesh with a pinion L⁴ 55 attached to the inner end of a horizontally-disposed shaft L⁵ journaled in the bracket A². The outer end of the shaft L⁵ is provided with a hand wheel L⁶ under the control of the operator to permit the latter to 60 turn the shaft L⁵ with a view to rotate the nut L² and thus cause an up or down movement to the screw rod L and consequently to the saddle K according to the direction in which the hand wheel L⁶ is turned at the 65 time.

The clamping or presser arm H is provided at its forward end with a roughened surface H' adapted to contact with the top of the rim stock F supported on the plates G and G'. The arm H is screwed or otherwise secured on the upper threaded end H² of a post H³ mounted to slide up and down in a bearing J⁷ forming part of the slide J, and the said post H³ is provided with a key-way H⁴ engaged by a key J⁸ held on the bearing J⁷ (see Fig. 7) so that the post H³ is held against turning but is free to slide up and down in the bearing J⁷. The post H³ is provided with a rack H⁵ in mesh with a gear wheel N secured on a shaft N' journaled in a bearing J⁹ forming part of the bearing J⁷, and on one outer end of the shaft N' is secured a handle N² adapted to be taken hold of by the operator for imparting a turning motion to the shaft N' so as to cause the gear wheel N to move the rack H⁵ and with it the post H³ and the arm H up or down according to the forward or backward swinging motion given to the handle N². By the arrangement described the presser arm H can be moved downward in firm contact with the top of the rim stock F 70 and with it the post H³ and the arm H up or down according to the forward or backward swinging motion given to the handle N². By the arrangement described the presser arm H can be moved downward in firm contact with the top of the rim stock F 75 and with it the post H³ and the arm H up or down according to the forward or backward swinging motion given to the handle N². By the arrangement described the presser arm H can be moved downward in firm contact with the top of the rim stock F 80 and with it the post H³ and the arm H up or down according to the forward or backward swinging motion given to the handle N². By the arrangement described the presser arm H can be moved downward in firm contact with the top of the rim stock F 85 and with it the post H³ and the arm H up or down according to the forward or backward swinging motion given to the handle N². By the arrangement described the presser arm H can be moved downward in firm contact with the top of the rim stock F 90 and with it the post H³ and the arm H up or down according to the forward or backward swinging motion given to the handle N². By the arrangement described the presser arm H can be moved downward in firm contact with the top of the rim stock F 95 and with it the post H³ and the arm H up or down according to the forward or backward swinging motion given to the handle N². By the arrangement described the presser arm H can be moved downward in firm contact with the top of the rim stock F 100 and with it the post H³ and the arm H up or down according to the forward or backward swinging motion given to the handle N². By the arrangement described the presser arm H can be moved downward in firm contact with the top of the rim stock F 105 and with it the post H³ and the arm H up or down according to the forward or backward swinging motion given to the handle N². By the arrangement described the presser arm H can be moved downward in firm contact with the top of the rim stock F 110 and with it the post H³ and the arm H up or down according to the forward or backward swinging motion given to the handle N². By the arrangement described the presser arm H can be moved downward in firm contact with the top of the rim stock F 115 and with it the post H³ and the arm H up or down according to the forward or backward swinging motion given to the handle N². By the arrangement described the presser arm H can be moved downward in firm contact with the top of the rim stock F 120 and with it the post H³ and the arm H up or down according to the forward or backward swinging motion given to the handle N². By the arrangement described the presser arm H can be moved downward in firm contact with the top of the rim stock F 125 and with it the post H³ and the arm H up or down according to the forward or backward swinging motion given to the handle N². By the arrangement described the presser arm H can be moved downward in firm contact with the top of the rim stock F 130 and with it the post H³ and the arm H up or down according to the forward or backward swinging motion given to the handle N².

The operation is as follows: The approximately semicircular rim stock F is placed in position on the supporting plates G and G' at the time the presser and clamping arm H is in a raised position and then the operator unlocks the handle N² and swings the same in the direction of the arrow a' so as to cause the arm H to move downward into contact with the top of the rim stock F to exert a downward pressure on the said stock and thus equalize the same on the support- 130

ing plates G and G'. It will be noticed that by the arrangement described the rim stock F is securely clamped in position on the supporting plates G and G' and the arm H is locked against movement for the time being by the bolt O engaging the toothed wheel O'. The operator now imparts an upward swinging motion to the handle J⁶ so that the pinion J⁴ imparts a traveling motion to the rack J³ and consequently to the slide J to move the supporting plates G and G', the arm H and the rim stock F inwardly toward the face of the cutter head C so that the cutters C' finally cut the inner side of the rim stock F to reduce the same absolutely true to the inner surface of the rim stock and when this has been done the handle J⁶ is swung downward to retard the slide J and the parts carried thereby, after which the handle N² is unlocked and swung in the reverse direction of the arrow a' to move the arm H upward out of engagement with the rim stock F which can now be removed from the machine and replaced by another one to be trued.

When it is desired to true short rim stock and on both sides, the following arrangement is made, special reference being had to Figs. 6, 7 and 8: The supporting plates G and G' instead of being attached to the outer ends of the blocks I and I' are fastened in grooves on the top of the said blocks I and I' and on the outer ends of the plates G and G' are secured stops P by the use of set screws P', and each stop is provided with a toothed bar P² fitting into the upper toothed face of the corresponding plate G or G', the bar being pressed firmly in place by a set screw P², as plainly indicated in Fig. 8. The rim stock F' is placed in position on the plates G, G' and clamped thereto by the use of the clamping arm H, as previously explained, and then the slide J is moved toward the face of the cutter head C so that the cutters C' reduce one side of the stock F' to the inner surface of the rim stock F'. When this has been done the slide J is returned and the arm H is raised to permit of reversing the stock F' on the plates G and G' and abutting the trued side of the rim stock on the stops P, after which the arm H is moved downward to clamp the rim stock F' again in position. The slide J is now again moved toward the face of the cutter head C so that the cutters C' reduce the other side of the rim stock true to the opposite side and to the inner surface of the rim stock. A stop screw Q screws in the forward end of the saddle K and is adapted to be engaged by the hub of the wheel O' to limit the movement of the slide J toward the face of the cutter head C so that the stock F' is reduced to a predetermined width. After the rim stock F' has been trued at both sides relative to the inner

surface of the stock, the latter is removed from the machine and another one placed in position thereon, and the above-described operation is repeated to reduce both sides of the stock true to the inner surface thereof and to a predetermined width. 70

Having thus described my invention, I claim as new and desire to secure by Letters Patent:

1. In a wheel rim truing machine for truing one side of the rim stock relative to the inner face thereof, the combination with a revoluble cutter head having cutting edges extending in the same plane, of a rim stock support having movement toward and from the said cutter head and provided with spaced supporting means at a right angle to the face of the said cutter head and adapted to support the rim stock at the inner surface and at opposite sides thereof, 75 and a pressure device adapted to engage the rim stock exteriorly at the middle thereof. 80

2. In a wheel rim truing machine for truing one side of the rim stock relative to the inner face thereof, the combination with a revoluble cutter head having its cutting edges extending in the same plane, of a saddle provided with spaced parallel supports at a right angle to the said plane and adapted to support the rim stock at the inner surface and at points between the ends thereof, a clamping device adapted to engage the top of the rim stock at a point approximately half way between the supported points, the said clamping device being adjustably mounted on the said saddle, means for raising and lowering the said clamping device on the said saddle, and means for moving the said supports toward and from the said cutter head. 95 100

3. In a wheel rim truing machine for truing one side of the rim stock relative to the inner face thereof, the combination with a revoluble cutter head having its cutting edges extending in the same plane, of a saddle provided with spaced parallel supports at a right angle to the said plane and adapted to support the rim stock at the inner surface and at points between the ends thereof, a clamping device adapted to engage the top of the rim stock at a point approximately half way between the supported points, the said clamping device being adjustably mounted on the said saddle, means for raising and lowering the said clamping device on the said saddle, means for moving the said supports toward and from the said cutter head, and means for raising and lowering the said saddle independent of the said means for raising and lowering the said clamping device. 115 120

4. In a wheel rim truing machine for truing one end of the rim stock relative to the inner face thereof, the combination with a cutter head provided on its face with a 130

- cutter, the edges of which extend approximately in the same vertical plane, of a saddle in front of the face of the cutter head, means for raising and lowering the said saddle, spaced supporting plates on the said saddle and standing at a right angle to the face of the said cutter head, the said supporting plates being adapted to support the rim stock at the inner face and adjacent the ends thereof, a clamping arm mounted on the saddle and adapted to engage the rim stock exteriorly and at the top thereof at a point approximately midway between the points of support of the rim stock, means for moving the said clamping arm up and down independent of the up and down movement given to the said saddle, and means for moving the said supporting plates on the saddle toward and from the face of the said cutter head.
5. In a wheel truing machine for truing one side of the rim stock relative to the inner face thereof, the combination with a revoluble cutter head provided at its face with cutters having their cutting edges extending approximately in the same vertical plane, of a saddle in front of the said cutter head, means for raising and lowering the said saddle, a slide mounted to slide on the said saddle, means for moving the said slide toward or from the face of the said cutter head, supporting plates held on the sides of the said slide and adapted to support the rim stock at the inner face thereof, a presser arm adapted to engage the top of the rim stock and provided with a vertical post mounted to slide up and down on the said slide, and manually-controlled means engaging the said post for moving the latter up and down independent of the said means for raising and lowering the saddle.
6. A wheel rim truing machine provided with spaced parallel supporting plates adapted to be engaged by the inner surface of a rim stock, and a pressure device adapted to engage the rim stock exteriorly at a point half way between the points of support of the rim stock on the said supporting plates, and means for moving the said pressure device in and out of engagement with the rim stock on the said supporting plates.
7. A wheel rim truing machine provided with a saddle having guideways, a slide mounted to slide on the said guideways and provided with spaced supporting plates for engagement by the inner surface of a rim stock to be trued, a clamping arm mounted to move up and down on the said slide and adapted to engage the top of the rim stock,

and manually-controlled means for moving the said clamping arm up and down.

8. A wheel rim truing machine provided with a saddle having guideways, a slide mounted to slide on the said guideways and provided with spaced supporting plates for engagement by the inner surface of a rim stock to be trued, a clamping arm extending horizontally and adapted to engage the rim stock exteriorly at a point half way between the points of support of the rim stock on the said supporting plates, a post provided with a rack and carrying the said clamping arm, the said post being mounted to slide up and down on the said slide, a transverse shaft journaled on the said slide, a pinion on the said shaft engaging the said rack, and a handle on the said shaft for turning the latter to raise and lower the said post and its arm.

9. A wheel rim truing machine provided with a saddle having guideways, a slide mounted to slide on the said guideways and provided with spaced supporting plates for engagement by the inner surface of a rim stock to be trued, a clamping arm extending horizontally and adapted to engage the rim stock exteriorly at a point half way between the points of support of the rim stock on the said supporting plates, a post provided with a rack and carrying the said clamping arm, the said post being mounted to slide up and down on the said slide, a transverse shaft journaled on the said slide, a pinion on the said shaft engaging the said rack, a handle on the said shaft for turning the latter to raise and lower the said post and its arm, and a locking device for locking the said arm in the adjusted position.

10. A wheel rim truing machine provided with a saddle having guideways, a slide mounted to slide on the said guideways and provided with spaced supporting plates for engagement by the inner surface of a rim stock to be trued, adjustable stops secured to the said supporting plates, limiting means between the saddle and the said slide to limit the feeding movement of the latter, a clamping arm mounted to move up and down on the said slide and adapted to engage the top of the rim stock, and manually-controlled means for moving the said clamping arm up and down.

In testimony whereof I have signed my name to this specification in the presence of two subscribing witnesses.
